RECEPTACLE FOR SPOONS OR THE LIKE

Abe Hirsch, New York, N. Y.

Application October 24, 1952, Serial No. 21,973

Term of patent 3½ years

(CL. D44—29)

To all whom it may concern:

Be it known that I, Abe Hirsch, a citizen of the United States of America, residing in New York city, county of New York, and State of New York, have invented a new, original, and ornamental Design for a Receptacle for Spoons or the like, of which the following is a specification, reference being had to the accompanying drawing, forming part thereof, wherein:

Figure 1 is a front perspective view of a receptacle for spoons or the like, showing my new design.

Figure 2 is a top plan view of same, and

Figure 3 is a rear elevational view thereof.

The characteristic features of my design reside in the portions shown in full lines in the drawing.

I claim:

The ornamental design for a receptacle for spoons or the like, substantially as shown and described.

ABE HIRSCH.
